DESIGN FOR A LAWN SPRINKLER HEAD

Samuel G. Weber, Pasadena, Calif.

Application July 6, 1936, Serial No. 63,666

Term of patent 3½ years

To all whom it may concern:

Be it known that I, Samuel G. Weber, a citizen of the United States and residing at Pasadena, in the county of Los Angeles and State of California, have invented a new, original, and ornamental Design for a Lawn Sprinkler Head, of which the following is a specification, reference being had to the accompanying drawing, forming a part thereof.

In the accompanying drawing, Fig. 1 is a front view of a lawn sprinkler head showing my new design;

Fig. 2 is a side elevation;

Fig. 3 is a rear view; and

Fig. 4 is a top plan view thereof.

I claim:

The ornamental design for a lawn sprinkler head substantially as shown.

SAMUEL G. WEBER.
